UNITED STATES PATENT OFFICE

HAROLD J. BRUNK, OF CHICAGO, ILLINOIS, ASSIGNOR, BY MESNE ASSIGNMENTS, TO THE C. F. PEASE COMPANY, A CORPORATION OF DELAWARE

AUTOMATIC BELT ADJUSTER

Application filed February 24, 1927. Serial No. 170,560.

My invention relates to improvements in automatic belt adjusters.

In using endless belts of fabric or other material on machines for making blueprints, machines for drying the same, or on paper making machines where a wire screen is used, and in fact on all machines of like character, difficulty is always encountered in preventing the travel of the belt from side to side on the supporting rollers. Various manually operated adjustments have been provided heretofore, but as they require manipulation and depend on the judgment of the operator, the results are seldom satisfactory. Where one of the rollers is adjustable, the operator usually draws one end of said roller toward himself to cause the belt to travel toward its normal position and if it subsequently moves too far he draws the other end toward him, and so on, continually moving the adjustable roller farther away from the other roller or rollers. Thus the belt is stretched and eventually breaks. Furthermore, the operator frequently adjusts the roller in the wrong direction since the operation is just the reverse from what it would be with a leather belt traveling on a crowned pulley.

The object of the present invention is to overcome these difficulties by providing means for automatically moving the belt back and forth toward its normal position when it travels toward one side or the other.

In the accompanying drawings, the invention is illustrated as being embodied in a blueprint drying machine, although it is adapted for use in numerous other classes of service.

Figure 1 is a sectional elevation of part of a machine for drying photographic prints.

Fig. 2 is a top plan view of the front portion thereof.

Fig. 3 is an enlarged plan view, partly in section, of the same portion.

Fig. 4 is a sectional elevation of said portion of the machine.

Fig. 5 is a section on line 5—5, Fig. 4.

Fig. 6 is a section on line 6—6, Fig. 4.

Fig. 7 is a section on line 7—7, Fig. 4.

Fig. 8 is an enlarged sectional elevation of

certain mechanism for limiting the number of turns of the automatic adjusting device.

Fig. 9 is a section on line 9—9, Fig. 8.

Fig. 10 is a section on line 10—10, Fig. 8, and

Fig. 11 is an enlarged sectional elevation of a modification of one end of the adjustable roller.

Blueprint drying machines may include suitable side-frame members 10 carrying between them rollers 11, 12, 13 and 14, and a drying drum 15. An endless belt 16 passes over the guide rollers 11, 12, 13 and 14, and part way around the drying drum 15. Said drum is heated by any suitable means (not shown) and the blueprints or other prints to be dried are laid on the belt 16 and travel in the same direction of the arrow in Fig. 1, being carried around the heating drum and dried.

The belt 16 may be several feet wide and may be made of fabric, such as canvas, for example. Even though said belt is properly adjusted initially, it may elongate, due to the continual feeding of wet paper on one side or the other, as well as in the middle, permitting said belt to stretch more and more. This stretching at the side tends to cause the belt to travel from the middle to one side or the other. In a machine of this character, the difficulties, due to side travel of the belt, are probably greater than in machines of any other types, and such a machine therefore will illustrate well the advantages of the present invention.

Generally speaking, the construction of the automatic belt adjuster is such that the roller or cylinder 11 rotates freely about its supporting shaft 17, but has at each end means actuated by the belt, for causing positive engagement between said roller and said shaft, whereby the two will turn concurrently. At one end the engagement is direct, so that the roller turns in the same direction as the shaft, whereas at the other end there are interposed planetary gears whereby the shaft is made to rotate in the opposite direction from said roller. The shaft is pivotally supported at one end on a vertical axis, the other end being free to move back and forth a short distance

in a horizontal plane in the arc of a circle. The rotation of said shaft about its own axis, in one direction or the other, causes said other end to swing back and forth, thereby causing the belt to travel from one side toward the other, in a direction to restore it to normal position, its movement away from normal position causing the rotation of said shaft, in one direction or the other.

10 This mechanism will now be described more in detail. Referring to Figs. 3 and 4, a casting 18 is adjustably mounted on a screw threaded rod 19 secured to the frame 10 of the machine and has a vertical pivot pin 20 forming a pivotal support for the right-hand end of the shaft 17 by virtue of an apertured web 21 on a member 22 which carries a ball bearing raceway 23 mounted on the end of said shaft. A pinion 24 (see Fig. 5) is secured to said shaft and meshes with one or more pinions 25 mounted on a shaft or shafts 26 supported in the member 22. The pinion 25 meshes with an annular gear 27 secured to a ring 28 carrying a circular member 29 (see Fig. 6) with ratchet teeth 30 on its periphery.

15 In order to lock the cylindrical roller 11 to the shaft 17, I may provide a number of pivoted pawls 31 near the end thereof, arranged to project outwardly through slots in said roller, said pawls being pivoted at 32 to a casting 33 arranged to rotate freely on the shaft 17 and supporting the end of said roller. A preferred form of pawl is shown in Fig. 11, hereinafter referred to. Springs 34 are 20 mounted in recesses in the casting 33 and normally press the pawls outwardly, whereby they normally clear the ratchet teeth 30. The roller 11 and casting 33 turn together, the latter turning freely about the shaft 17 on a ball-bearing raceway 35, the other end of said roller also turning on ball-bearings as herein-after described.

25 The belt 16, under normal conditions, occupies the dotted line position, shown in Fig. 2; that is to say, it is arranged centrally on the roller 11. However, if it should travel to the right, it would depress the pawls 31 against their springs, causing said pawls to engage the ratchet teeth and thereby rotate the planetary gears 24, 25 and 27, thereby rotating shaft 17 in the opposite direction, this rotation resulting in moving the left hand end of said shaft away from the operator, in other words inwardly, whereupon the belt travels 30 slowly back toward mid-position until further correction is required.

35 At the left hand end of said roller 11 (Fig. 4) a somewhat similar arrangement is provided, including pawls 36 pivotally supported at 37, in a casting 38, which supports the end of said roller (Fig. 7.) said casting being freely rotatable about the shaft 17 on a ball-bearing raceway 39. The pawls 36 are normally held in outward position by springs 40, mounted in recesses in the casting 38. The

end of the cylinder is closed by a circular plate 41, fast on the shaft 17 and having ratchet teeth 42 on its periphery to be engaged by the pawls 36 when the belt works over to the left hand end of said roller (as viewed from the front of the machine), thereby causing the roller and the shaft to turn together and actuate mechanism for moving that end of the shaft outwardly; that is, toward the operator.

45 The mechanism for moving the end of the shaft back and forth in the arc of a circle, causing the belt to move from one side of the roller toward the middle thereof, will now be described. The left-hand end of the shaft 17, shown in Fig. 4, is supported in a ball-bearing raceway 43 mounted in a traveling head 44, which is provided with upper and lower rollers 45, permitting it to move back and forth on flat surfaces provided in the yoke 46, and has a third roller 47 engaging the head of a bolt 47' to limit end movement of the shaft 17. Said shaft has a worm gear 48 near the end thereof meshing with a gear 49 mounted on a shaft 50. The rear end of said shaft, as shown in Fig. 8, has a universal joint 51 with an extension shaft 52, whereby a head 53 and a cylinder 54, in which said head is received, may be rotated in one direction or the other, depending on the rotation of the shaft 17, said head and cylinder having a splined connection (See Fig. 9). Said cylinder carries a plurality of springs 55 which press radially inward on corresponding plungers 56 maintaining the latter in engagement normally with ratchet teeth 57 on the periphery of a cylindrical member 58 received within said cylinder 54. See Figs. 8, 9 and 10. Said cylindrical member 58 has a screw threaded shaft 59 at one end which may rotate in a fixed nut 60 secured to the frame of the machine whereby rotation of said cylindrical member in one direction or the other will cause it to move toward the front or rear of the machine. Said member has a groove 61, which when the belt is traveling properly, is positioned about midway between the two plungers 56. The cylindrical member 58 has a shaft 62 projecting from its end supported in a sliding head 63. A screw 64 or other suitable means holds the head 63 to the head 53, although in this particular machine the axle of roller 14 is, in practice, received in bearings which are spring impelled in a direction to maintain tension on the belt and thus the sliding head 63 would be drawn rearwardly, in any case, without this fastening. The rear end of the cylinder 54 is provided with a groove 65 which receives a lug 66 secured to the frame 10 (Fig. 3) thereby preventing longitudinal movement of said cylinder during its rotation.

55 It will be seen the arrangement is such that upon rotation of the cylinder 54 one of

the plungers will engage the adjacent ratchet teeth causing rotation of the cylindrical member 58, the other plunger 56 sliding over the inclined surfaces of its corresponding ratchet teeth, said ratchets facing in opposite directions. As a result, the middle part of the cylindrical member 58 travels toward the plunger which is causing its rotation until said plunger slides into the groove 61, whereupon the cylinder 54 continues to rotate without rotating the cylindrical member 58. In other words, the mechanism provides for a predetermined number of rotations of the cylindrical member 54. When the cylinder 15 rotates in the opposite direction, the other plunger 56 becomes effective to rotate the cylindrical member 58 in the opposite direction, thereby causing it to slide in a direction the reverse of the sliding movement just described. With this construction, as the belt 20 gradually works to the left-hand end of the roller 11, as seen in Fig. 2 for example, the supporting shaft 17 begins to rotate in the same direction that roller 11 is rotating, and 25 at the same time its left-hand end is swung outwardly a little, about the right-hand end as a pivot, causing the belt to travel back toward its central position.

A preferred form of pawl and ratchet mechanism is shown in Fig. 11, at the ends of the roller 11, the pawls 67 being pivoted at the opposite ends, as compared with those previously described, and having pins 68 projecting therefrom, which pins normally clear 30 a series of openings 69 in a plate 70, secured to the shaft 17. Said openings are spaced equidistant from each other and at the same radii from the center of said shaft, whereby the pins 68, when projected outwardly by the 35 rotation of the pawls 67 about their pivotal supports, will enter the nearest opening and thus lock the roller 11 to the shaft 17, or at the other end of said roller will cause the 40 operation of the planetary gears. Said pawls are of such configuration that the belt 45 does not ride up on them gradually as with the first pawls described, but engages the top surface of the pawl as the roller is turning and as said pawl is passing from one span 50 of the belt to the other, provided said belt has worked far enough to one side to overlie the top corner of said pawl, as it appears in dotted lines in said figure. With this 55 arrangement, a comparatively small movement of the belt to one side or the other from normal position will result in rendering the pawls fully effective.

As the return movement of the belt takes place very slowly (possibly an hour to an 60 hour and a half under some conditions) the adjustable end of the shaft will not require any more movement than what is sufficient to start the return movement of the belt. For this reason, the correction is limited to that 65 corresponding to a definite determined num-

ber of rotations of the correcting mechanism, otherwise the belt would be stretched at one side and possibly torn or broken. It is almost impossible to obtain wide belts or bands of this character which are of exactly the 70 same length on both edges, and for that reason the travel of the belt one way or the other begins almost immediately. When a new belt is applied, and after the roller has been properly adjusted, it may continue to travel in 75 midposition for several hours, except as it may be effected by unusual conditions. For example, placing blueprints more on one side of the belt than on the other not only will cause an increased thickness when the prints are traveling around the heating drum, but the moisture from the wet prints will cause 80 a change in the length of one side of the belt as compared with the other.

With the improvements described herein, 85 however, all these irregularities are automatically compensated for, and the belt confined to a position not far removed from its theoretically perfect location. Under some conditions, the edge of the belt is irregular 90 so that the pivoted pawls work intermittently as parts of said edge overlap them. In either case, however, the mechanism operates to relieve the operator of the necessity of the manual adjustment. Furthermore, the 95 life of the belts is greatly prolonged as, with the automatic adjustment, the roller remains in the same average position at all times, whereas with the previously used manual adjustment, the tendency was to move the roller 100 farther and farther away from the other rollers over which the belt traveled, thereby continually stretching it. With my improvement as the belt stretches gradually, due to continued use, the roller 14 takes up the 105 slack, and the right hand end of the roller 11 and shaft 17 may be moved outwardly to whatever extent is necessary, by manual adjustment of the screw threaded rod 19 passing through the casting 18, without effecting 110 the automatically operated means for maintaining the belt in midposition.

What I claim as new is:

1. The combination with a frame, of a roller, a pivotal support for one end of said roller, adjustable longitudinally of said frame, a carrier for the other end of said roller, wheels thereon, a track associated with said frame, on which said rollers and carrier are permitted a limited movement longitudinally of said frame in either of two directions from mid-position, a belt traveling over and rotating said roller, means actuated by said belt upon deviation thereof from its normal position between the ends of said 115 roller for moving said carrier along said track to shift the axis of rotation of said roller and cause said belt to travel in a direction opposite to said deviation movement, and means for stopping the travel of said carrier be- 120 125 130

fore it reaches the limit of said movement permitted it by said track.

2. The combination with a rotatable shaft and a roller normally rotatable thereon, of a belt passing over said roller, and a pawl and ratchet mechanism near one end of said roller normally inoperative but rendered operative by said belt overlying said pawl, means carried by said roller for causing said shaft to rotate in the opposite direction from said roller and means cooperating with said shaft when rotating to vary its axis of rotation.

3. In combination, a pair of side frames, a shaft extending between the two, a pivotal connection between one end of said shaft and one side frame, means arranged to slide back and forth on said other side frame and carrying the other end of said shaft, a roller normally rotatable about said shaft, a pawl and ratchet mechanism associated with each end of said roller and shaft to mechanically connect the roller and shaft, one pawl and ratchet being arranged to lock said roller to said shaft causing the same to turn together, gearing associated with the other pawl and ratchet mechanism to cause said shaft to rotate in the opposite direction from said roller when said pawl and ratchet engage each other and means whereby the rotation of said shaft causes said first means to slide one way or the other, not to exceed a predetermined distance.

4. In combination, a pair of side frames, a shaft extending between the two, a pivotal connection between one end of said shaft and one side frame, means arranged to slide back and forth on said other side frame and carrying the other end of said shaft, a roller normally rotatable about said shaft, a pawl and ratchet mechanism associated with each end of said roller and shaft to mechanically connect the roller and shaft, one pawl and ratchet being arranged to lock said roller to said shaft causing the same to turn together, and gearing associated with the other ratchet mechanism to cause said shaft to rotate in the opposite direction from said roller when said pawl and ratchet engage each other, a belt passing over said roller, said pawls being arranged beyond the edges of said belt but adapted to be engaged by one edge or the other when said belt deviates from its normal position on said roller.

5. In combination, a pair of side frames, a shaft extending between the two, a pivotal connection between one end of said shaft and one side frame, means arranged to slide back and forth on said other side frame and carrying the other end of said shaft, a roller normally rotatable about said shaft, a pawl and ratchet mechanism associated with each end of said roller and shaft to mechanically connect the roller and shaft, one pawl and ratchet being arranged to lock said roller to said shaft causing the same to turn together,

gearing associated with the other pawl and ratchet mechanism to cause said shaft to rotate in the opposite direction from said roller when said pawl and ratchet engage each other, a belt passing over said roller, said pawls being arranged beyond the edges of said belt but adapted to be engaged by one edge or the other when said belt deviates from its normal position on said roller, and means for moving the slideable end of said shaft back and forth a predetermined amount depending on the direction of rotation of said shaft.

6. In a device of the class described, a rotatable shaft, a roller surrounding the same and normally turning freely thereon, said roller having a slot at each end, a pawl pivoted near each slotted end and projecting through the same above the surface of the roller, ratchet mechanism associated with said pawls normally out of engagement therewith, a planetary gear system associated with one ratchet and with said shaft to cause the shaft to rotate in a direction opposite to that of said roller when said pawl and ratchet are in engagement, the other ratchet serving to cause said shaft to turn with said roller when the corresponding pawl engages said ratchet, and a belt passing over said roller between said pawls and normally clearing the same but adapted upon travel toward either end of said roller to overlie one pawl or the other to cause the engagement thereof with the corresponding ratchet.

7. In a device of the class described, a rotatable shaft, a roller surrounding the same and normally turning freely thereon, said roller having a slot at each end, a pawl pivoted near each slotted end and projecting through the same above the surface of the roller, ratchet mechanism associated with said pawls normally out of engagement therewith, a planetary gear system associated with one ratchet and with said shaft to cause the shaft to rotate in a direction opposite to that of said roller when said pawl and ratchet are in engagement, the other ratchet serving to cause said shaft to turn with said roller when the corresponding pawl engages said ratchet, a belt passing over said roller between said pawls and normally clearing the same but adapted upon travel toward either end of said roller to overlie one pawl or the other to cause the engagement thereof with the corresponding ratchet, a sliding support forming a bearing for one end of said shaft, and means actuated by the rotation of said shaft for moving said bearing back or forth in a direction to cause said belt to return toward its normal position on said roller.

8. An attachment for photoprint dryers having a roller and a belt passing over the same comprising, a rotatable shaft, a worm and gear connection at one end thereof, a sliding support for said worm and gear, a

shaft rotated by said gear having oppositely disposed ratchet surfaces, a pair of pawls engaging said surfaces and rotatable with said gear, whereby one pawl may rotate the 5 ratchets in one direction and the other pawl in the other, and means for causing a longitudinal movement of said ratchet surfaces during rotation thereof, whereby said pawls are caused to slide along said ratchets during 10 such rotation toward the end thereof whereupon one or the other of said pawls becomes disengaged from the corresponding ratchet thereby terminating the rotation thereof.

9. An attachment for photoprint dryers 15 having a roller and a belt passing over the same, of a shaft supporting said roller having a pivotal support at one end and a sliding head constituting a bearing at the other end, a stationary nut, a screw-threaded shaft 20 passing through the same associated with said shaft at said head, a clutch whereby said roller shaft may rotate said screw-threaded shaft in one direction or the other to cause a longitudinal movement thereof 25 and thus slide said head back and forth, and means for rendering said clutch ineffective after a predetermined number of rotations.

10. In a device of the class described, a 30 rotatably mounted shaft, ball bearing raceways on said shaft on opposite ends thereof, two members surrounding said shaft and turning on said ball bearings, each member having a plurality of pawls pivoted thereto, a spring associated with each member and 35 each pawl normally pressing the same outwardly, a roller also supported on said members and having slots near its ends through which the pawls project, and a belt partially surrounding said roller and rotating the 40 same but normally clearing said pawls, a ratchet member associated with each end of said shaft and arranged to be engaged by the corresponding pawls when the latter are depressed by said belt traveling to one side of 45 its central position to cause such engagement of said pawls with the corresponding ratchet, and planetary gearing associated with one of said ratchets for rotating said shaft in a direction the reverse of that of said roller.

50 11. An attachment for photoprint machinery having a roller and a belt passing over the same, comprising a shaft supporting said roller having a pivotal support at one end and a sliding head constituting a 55 bearing at the other end, a stationary nut, a screw-threaded shaft passing through the same associated with said shaft at said head, a clutch whereby said roller shaft may rotate said screw-threaded shaft in one direction or the other to cause a longitudinal movement thereof and thus slide said head back and forth, means for rendering said clutch ineffective after a predetermined number of rotations, said roller having pawls 60 65 associated with the end thereof, a disc asso-

ciated with each end of said roller and having perforations therein to be engaged by one end of a pawl, and gearing associated with one of said discs and said supporting shaft to rotate the latter in a direction the reverse of the rotation of said roller, the pawl and disc at the other end being arranged to rotate the shaft with said roller, whereby said belt may depress a pawl at one end or the other of said roller to cause rotation of said shaft in one direction or the other.

In testimony whereof, I have subscribed my name.

HAROLD J. BRUNK.
